ICE MAKING APPARATUS

William H. Taylor, Muskego, Wis., assignor, by
mesne assignments, to Reconstruction Finance
Corporation, Chicago, Ill., a corporation

Application February 2, 1935, Serial No. 4,670

15 Claims. (Cl. 62—106)

The present invention relates to improvements in the construction and operation of apparatus for congealing liquid and for separating the congealed substance from excess liquid.

5 Generally defined, an object of the present invention is to provide improved ice making or liquid congealing apparatus, which is simple and compact in construction, and which has relatively great capacity.

10 Another object of the invention is to provide an improved liquid congealing machine which can be conveniently built in units of various capacity, and which is entirely automatic in operation when once set for a predetermined output.

15 A further object of the invention is to provide new and useful apparatus for effectively separating ice particles or crystals from excess liquid, without danger of clogging the separator.

20 Still another object of the invention is to provide an ice producing unit which is continuously functioning, and which is operable with minimum power consumption and attention.

25 An additional object of the invention is to provide a durable congealed liquid producing machine wherein danger of escape of refrigerant is eliminated, and which has maximum efficiency in operation.

30 Another object of the invention is to provide an automatic ice machine which can be manufactured and operated at relatively low cost, and which may be safely manipulated.

35 These and other objects of the present invention will be apparent from the following detailed description.

40 A clear conception of one embodiment of the several features constituting the present improvement, and of the mode of constructing and of operating ice making apparatus manufactured in accordance with the improvement, may be had by referring to the drawing accompanying and forming a part of this specification, wherein like reference characters designate the same or similar parts in the several views.

45 Fig. 1 is a more or less diagrammatic central vertical section through the improved ice making apparatus including the liquid congealing and excess liquid separating structures; and

50 Fig. 2 is a transverse horizontal section through the liquid congealing structure taken along the line 2—2 of Fig. 1, and also shows a top view of the excess liquid separator.

55 Although the invention has been shown herein as being specifically applied to a machine for converting water into relatively dry or de-watered

slush-ice, it is not the intent to thereby unnecessarily restrict the scope, since some of the new features may obviously be susceptible of more general application; and this is especially true of the excess liquid separator.

5 Referring to the drawing, the present improved ice making apparatus comprises, in part, a liquid congealing unit consisting generally of a main casing 4 having mounted therein one or more substantially upright long tubes 5 provided 10 with internal bores or cooling surfaces 6 and exposed externally to a common refrigerant confining chamber 7; a liquid supply pipe 8 for supplying abundant but regulated quantities of liquid to the upper open ends of the tubes 5; a revolving 15 scraper 9 having staggered cutting lugs 10 co-operable with the adjacent cooling surface 6 and supported within each tube 5 by means of a shaft 11; a removable upper casing 12 secured to the main casing 4 by cap screws 13 and having bearings 14 for rotatably supporting all of the scraper shafts 11; intermeshing gears 15 secured to the upper ends of the shafts 11 for imparting rotary motion thereto; and a driving 20 group.

25 While the main casing 4 of the congealing unit illustrated is provided with only three tubes 5, the number of these tubes actually utilized will depend upon the desired capacity of the machine, 30 and may range from a single tube 5 to several dozen or more. In actual commercial construction, the tubes 5 may be formed by cutting standard tubing into proper lengths and subsequently welding or otherwise fastening the individual 35 tubes 5 in place, and these tubes are preferably of relatively small internal diameter and of relatively great length. The refrigerant confining chamber 7 is preferably provided with a lower refrigerant supply connection 17 and with an 40 upper refrigerant outlet or exhaust connection 18, and these connections may be associated with any desired portion of the casing 4.

45 The liquid supply pipe 8 may be provided with a suitable control valve, and the admitted fresh liquid may accumulate to a variable depth within the upper basin 19 formed by the casing 4, depending upon the number and diameters of the tubes 5, and upon the rate of liquid supply. The outer wall of the casing 4 at the chamber 7 may 50 be insulated in order to prevent undesirable heating from the ambient atmosphere, and each of the scrapers 9 may be provided at its upper end with a spiral auxiliary scraping arm 20 cooperable with the upper tube-sheet 21 of the casing 4 55

to prevent ice deposits from forming on this sheet. As previously indicated, the cutting lugs 10 of each scraper 9 are staggered, so that each rotation of the scraper will cause the plural lugs 10 thereof to cooperate with all portions of the bore or cooling surface 6 within which the scraper is disposed; and by virtue of the fact that the scraper blades are radially disposed and are separated by intervening spaces, the liquid from 10 within the basin 19 can gravitate freely and in abundant quantities along the cooling surfaces 6. These intervening spaces also provide for escape of the removed ice films, these ice particles being washed downwardly by the excess liquid and the resulting slush-ice being delivered by gravity into a lower receptacle 22 as shown in Fig. 1.

In addition to the liquid congealing unit above described, the present improved apparatus also comprises improved mechanism for continuously 20 de-watering the slush-ice. This liquid separator consists of a series of elongated, inclined rods or bars 23 fixedly mounted within the receptacle 22 beyond the congealing unit; and a series of flights 24 carried by endless chains 25 for movement in 25 succession longitudinally over the bars 23.

The bars 23 may be taut wires having sufficient resiliency to permit slight lateral deflection, but should be capable of sustaining considerable load without excessive sagging. The flights 24 are successively movable through the liquid within the receptacle 22 and are adapted to transport the slush-ice upwardly along the bars 23 and out of the liquid basin. The liquid thus separated from the ice particles may escape from the receptacle 22 through an outlet 26, and the relatively dry ice crystals are discharged from the separator by the flights 24 into a delivery chute 27 located beyond the end of the receptacle 22. The flight carrier chains 25 may be supported upon sprockets 28 and driven by another chain 29, or otherwise, and the separating mechanism may be protected by a removable enclosure, not shown.

During normal operation of the improved ice making apparatus, the scrapers 9 are being revolved within the tubes 5 by power applied to the pulley 16 and through the gears 15 to the shafts 11, and the flights 24 and chains 25 are being driven in the direction of the arrow in Fig. 1, by power applied to the sprockets 28 through the driving chain 29. Fresh liquid is being supplied in regulated quantities through the supply pipe 8 to the basin 19, and this liquid is passing in abundant quantities downwardly through the tubes 5. The refrigerant confining chamber 7 is being supplied with refrigerant through the inlet connection 17, and the spent refrigerant is being withdrawn from the exhaust connection 18. As the fresh liquid flows along the internal cooling surfaces 6 of the tubes 5, this liquid is congealed and forms successive ice films upon the surfaces 6, and the revolving cutters 10 of the scrapers 9 constantly remove this ice film from the surfaces 6. The ice crystals thus removed 65 are carried downwardly through the tubes 5 by the excess liquid flowing between the radiating blades of the scrapers, and the mixture of excess liquid and ice crystals is delivered into the lower receptacle 22 through the lower ends of the tubes 5. This congealing action takes place continuously, and due to the staggered disposition of the cutters 10, the entire interior of each tube 5 is freed from ice during each revolution of the corresponding scraper 9.

75 The slush-ice delivered into the receptacle 22

flows toward the separator and upon the upper surface of the deck formed by the elongated elements or bars 23. The successive flights 24 passing through the slush-ice and beneath the level of the liquid in the receptacle 22, remove batches 5 of the slush-ice and carry it upwardly along the bars 23. The ice particles are transported out of the liquid, and the excess liquid drains off through the spaces between the bars 23 and is eventually discharged through the outlet 26 from 10 whence it may be returned to the inlet pipe 8. The separated ice crystals are in relatively dry condition when they reach the upper ends of the inclined bars 23, and are subsequently discharged by gravity through the delivery chute 27. 15 The lateral resiliency of the bars 23 will effectively prevent clogging of the separating deck, by the ice crystals which are transported longitudinally along this deck. While slight quantities of ice may escape with the separated liquid through 20 the outlet 26, this entrained ice serves to pre-cool the fresh liquid delivered to the basin 19, and thereby produces more rapid congealing action in the ice making unit. The scrapers 28, 25 associated with the upper ends of the revolving scrapers 9, serve to prevent accumulations of ice upon the upper tube-sheet 21, and the ice production is obviously continuous and is effected without danger of clogging due to ice accumulations. 30

From the foregoing description, it will be apparent that the invention provides improved ice making apparatus which is extremely simple and compact in construction, and which is, moreover, 35 continuous and automatic in operation. The ice making unit may readily be constructed of any desired capacity, and the separating mechanism insures delivery of a constant stream of relatively dry ice crystals, from the apparatus. The abundant supply of fresh liquid not only insures rapid 40 production of the successive ice films, but also maintains a flushing action along the cooling surfaces 6, and by utilizing the separated liquid delivered from the outlet 26, most efficient operation of the apparatus is assured. The entire 45 structure may be manufactured at relatively low cost, and may be operated to produce enormous capacity with minimum expenditure of power.

It should be understood that it is not desired to limit the invention to the exact details of construction and to the precise mode of operation herein shown and described, for various modifications within the scope of the claims may occur to persons skilled in the art.

It is claimed and desired to secure by Letters 5 Patent:

1. In combination, a series of elongated stationary tubes, means for cooling said tubes, means for supplying liquid to said tubes through the corresponding ends thereof, and rotary scrapers 6 within said tubes for delivering congealed liquid from the opposite ends thereof.

2. In combination, a casing forming a refrigerant chamber having a series of tubes extending therethrough, means for supplying liquid to the corresponding ends of all of said tubes, and movable means for removing congealed substance from the interiors of said tubes through the opposite corresponding ends thereof.

3. In combination, a stationary casing forming a refrigerant chamber having a series of substantially vertical elongated tubes passing therethrough, means for supplying liquid to all of said tubes through the upper ends thereof, and rotary scrapers within said tubes for removing

- congealed substance from the interiors thereof and for delivering the removed substance from the lower ends of said tubes.
4. In combination, a casing forming a refrigerant chamber having a series of elongated tubes passing therethrough and also forming a basin communicating with the corresponding ends of said tubes, means for supplying liquid to said basin, and a rotary scraper within each of said tubes for removing congealed substance from the interior thereof and for delivering the removed material from the opposite ends of said tubes.
5. In combination, a stationary casing forming a refrigerant chamber having a series of parallel elongated tubes passing therethrough and also forming a liquid basin communicating with the upper ends of said tubes, means for delivering refrigerant to said chamber, means for delivering liquid to said basin, and a rotary scraper within each of said tubes having a series of staggered cutting edges cooperable with the tube interior for removing congealed substance therefrom.
6. In combination, a casing forming a refrigerant chamber having a series of elongated tubes passing therethrough and also forming a basin having a bottom formed by one of the tube supporting sheets, means for supplying liquid to said basin, and a rotary scraper within each of said tubes for removing congealed substance therefrom, each of said scrapers having means for removing ice films from said tube supporting sheet.
7. In combination, a stationary casing forming a refrigerant chamber having a series of parallel vertical elongated tubes passing therethrough and also forming a basin communicating with the upper ends of said tubes, means for supplying refrigerant to said chamber, means for supplying pre-cooled liquid to said basin, a rotary scraper within each of said tubes having staggered cutting edges for removing congealed substance from the interiors thereof, means for conducting removed congealed substance from the lower ends of said tubes, and common means for propelling all of said scrapers.
8. In combination, means for producing a mixture of ice crystals and excess liquid, a series of elongated resilient elements disposed side by side and separated by elongated spaces, means for conducting said mixture to upper surfaces of said elements, and means for transporting the ice crystals along said elements while permitting the excess liquid to escape through said spaces.
9. In combination, means for constantly producing slush-ice containing excess liquid, a series of elongated laterally resilient elements spaced apart and forming a deck, means for conducting said slush-ice to the upper surface of said deck, and means for transporting the ice crystals of

said slush-ice along said elements while permitting escape of excess liquid through said spaces.

10. In combination, means for producing a mixture of ice crystals and excess liquid, a series of elongated resilient elements spaced apart and forming an inclined deck, means for conducting said mixture to the upper portion of the lower end of said deck, and means for transporting said mixture upwardly along said deck to remove the ice crystals from the excess liquid.

11. In combination, means for supplying slush-ice containing excess liquid, an inclined separating deck comprising a series of elongated elements extending at an inclination and separated by elongated spaces, means for conducting said slush-ice upon said deck, and a series of flights movable upwardly along the surface of said deck for transporting the slush-ice therealong.

12. In combination, means for constantly producing slush-ice containing excess liquid, a basin for receiving said slush-ice, a series of elongated inclined laterally spaced bars forming an inclined deck disposed within said basin, and means for removing said slush-ice from said basin and for urging the same upwardly along said deck.

13. In combination, means for producing slush-ice containing excess liquid, a basin for receiving said slush-ice as produced, a series of inclined bars extending from a medial portion of the bottom of said basin to an end thereof to form an inclined deck, a series of flights for transporting the slush-ice from said basin upwardly along said deck to remove the excess liquid therefrom, and means for returning said excess liquid to said slush-ice producing machine.

14. In combination, a casing forming a refrigerant chamber having a vertical tube passing therethrough and also forming a basin communicating with the upper end of said tube, means for supplying refrigerant to said chamber, means for supplying cooled liquid to said basin, a scraper within said tube, means for causing relative movement between the tube and scraper for removing congealed substance from the interior of the tube and delivering it from the lower end thereof, and means for conducting delivered congealed substance to a point remote from the tube.

15. In combination, a series of elongated stationary tubes, means for cooling said tubes, means for forming a basin for supplying liquid to said tubes through the corresponding ends thereof, a scraping rotor within each of said tubes for removing congealed liquid therefrom, and means carried by each of said rotors for preventing clogging of the inlet ends of said tubes by congealed liquid in said basin.

WILLIAM H. TAYLOR.
